UNITED STATES PATENT OFFICE.

EDWARD E. REDFIELD, OF GLENDALE, OREGON.

GUN-STOCK.

1,096,861.

Specification of Letters Patent. Patented May 19, 1914.

Original application filed January 28, 1913, Serial No. 744,627. Divided and this application filed September 9, 1913. Serial No. 788,849.

To all whom it may concern:

Be it known that I, EDWARD E. REDFIELD, a citizen of the United States, residing in Glendale, Douglas county, State of Oregon, have invented certain new and useful Improvements in Gun-Stocks, of which the following is a specification, reference being had to the accompanying drawings, which form a part hereof.

10 In another application filed January 28, 1913, Serial No. 744,627, of which this case is a division, there is shown and described an improved firearm developed with especial reference to the production of a small 15 caliber rifle which is adapted to be carried about conveniently.

This invention seeks to provide an improved folding skeleton stock which may be applied to firearms of any character or size 20 but which is especially useful in effecting the objects set out above in connection with the provision of a compact small caliber rifle. The improved stock is not only pivoted to the grip of the firearm so that it may be folded against the barrel but its members are pivotally connected and so arranged 25 that the stock itself folds in the same movement by which it is turned against the barrel so that it occupies little space and may 30 enter the holster with the barrel. Further, the supporting pivot pins of the stock are so arranged with respect to each other and the line of fold of the stock itself that the latter 35 passes within the line between the pins and the stock is accordingly held in folded position automatically and without the use of auxiliary retaining devices. The butt plate is formed as a single integral piece and when 40 the stock is in folded position lies parallel and in juxtaposition to the main frame members of the stock. This construction renders unnecessary the provision of separate reinforcing members for the butt plate, as when the latter itself is composed 45 of hinged sections. In the present stock the main frame members are preferably secured hingedly to the grip by two fixed hinge joints thus rendering the construction at once more simple and substantial than 50 would be the case were one or both of the pivotal supports movable in the grip.

Reference is now to be had to the accompanying drawings for a detailed description of the invention, in which—

55 Figure 1 is a view in side elevation of a

firearm which embodies the invention, the folding skeleton stock being shown by full lines in its extended position and by broken lines in its folded position. Fig. 2 is a fragmentary detail view on a somewhat larger 60 scale of a portion of the grip and the stock, the grip being broken away to show the spring latch for holding the stock in extended position.

In the firearm shown in the drawings the 65 barrel *a*, chambered to receive the cartridge, the magazine *b*, the receiver *c* in which the barrel *a* is detachably secured and the frame *d*, provided in this instance with a pistol-grip *d'*, may be constructed and arranged 70 substantially as usual.

Short barreled, pistol-grip rifles, or rifle-pistols, of the general type of that shown in Fig. 1 of the drawings, are commonly provided with skeleton stocks for the purpose 75 of steadyng the pistol in use and insuring greater accuracy. Such skeleton stocks, themselves of rigid construction, are detachably secured to the pistol-grips or are pivoted thereon so that they may be turned 80 forward and upward against the barrel. If the rigid skeleton stock is detachably connected to the pistol it can be placed alongside the pistol when detached and so take up little room, but time is lost in affixing it to 85 the pistol when the pistol is required for immediate use. On the other hand, if the rigid skeleton stock is pivoted to the pistol-grip it cannot be inserted into the holster with the pistol but must lie outside of the same and 90 besides being unsightly and liable to injury is more or less in the way, making the pistol 95 more or less cumbersome to handle.

The special purpose of the present invention has been to construct and arrange the 100 skeleton stock in such manner that the difficulties incident to the use of rigid skeleton stocks, whether detachable or pivoted, may be overcome. To this end the skeleton stock has its members pivotally connected so that the stock itself may fold into small compass, and is pivotally connected to the pistol-grip in such manner that the stock itself 105 folds as it is turned forward and upward against the barrel and is extended as it is turned downward and rearward into position for use. As shown particularly in Figs. 1 and 2, the skeleton stock consists of three separate members *d*² *d*³ and *d*⁴. The upper member *d*² is L-shaped, having a short arm 110

d^5 , and is fixedly pivoted in a vertical recess d^6 in the pistol-grip d^1 , as at d^7 . The lower longitudinal member d^4 is also fixedly pivoted in the same recess at its forward end, as at d^8 . The rear or butt member d^3 is formed as a single integral plate and has the two longitudinal members pivoted at its upper and lower ends, as at d^9 and d^{10} . A spring pressed plunger d^{11} , mounted in the grip-piece d^1 , engages a notch d^{12} at the forward extremity of the upper member d^2 so as to retain the stock in operative position. It will be noted also that the fixed pivot d^8 is outside of a line drawn from the pivot d^7 to the point at which the butt member d^3 touches the fore-end when the stock is turned forward and folded, as shown by broken lines in Fig. 1, so that in reaching this position the pivot d^{10} passes slightly beyond the center line and the stock is slightly sprung or put under stress so that when turned forward and folded, as shown in Fig. 1, it will remain in that position without the use of special retaining devices until it is pulled downward by the user. It will be seen that by placing the pivot d^7 of the upper member in rear of the pivot d^8 of the lower member, the butt member d^3 is sprung against the lower member as the stock is turned forward, carrying with it the upper member d^2 into parallelism with the lower member, and that the short arm d^5 of the upper member not only gives the stock the desirable width vertically at the point of union with the grip but permits the stock to be turned up against the barrel.

From the description above given it will be appreciated that the improved stock is not only especially suitable to perform its function as a stock, by reason of the rigidity secured through the fixed hinged joints and the single integral butt plate, but that its construction of only three movable parts, namely, the two side bars and the butt plate, all interconnected by simple pivot pins, facilitates its movement from extended position to folded position and vice versa. This facility of convenient operation is of prime importance in a device of this

character and in that respect alone the present stock commands itself to general use. 50

I claim as my invention:—

1. The combination with a firearm having a hand grip of a skeleton stock having a lower member pivoted to the grip-piece at 55 its forward end, an upper member having an L-shaped forward end pivoted to the grip-piece at its end, and means carried by the grip-piece and engaging the L-shaped end of the upper member to hold the same 60 in fixed position, the members being pivotally connected to each other.

2. The combination with a firearm having a hand grip of a skeleton stock having its upper and lower members pivoted to the 65 grip-piece, an integral rigid butt-piece pivotally secured to the rear ends of said upper and lower members, and means mounted on the grip-piece and engaging detachably one of said members to hold the stock in rigid 70 operative position.

3. The combination with a firearm having a hand grip, of a skeleton stock having its upper and lower members pivoted to the grip-piece at their forward ends, the former 75 in rear of the latter and having their rear ends pivotally connected to the butt piece, the pivot at the forward end of the lower member being outside of a line from the pivot of the upper member to the point 80 where the end of the stock rests when the stock is turned forward and folded.

4. The combination with a firearm having a hand grip, of a skeleton stock having its upper member formed with a short arm and 85 pivoted to the grip-piece at the extremity of said short arm, and its lower member pivoted at its forward end to the grip-piece at a point in front of the pivot of the upper member, and having the rear ends of both 90 upper and lower members pivoted to the upper and lower ends of the butt piece.

This specification signed and witnessed this 2nd day of September, A. D., 1913.

EDWARD E. REDFIELD.
